UNITED STATES PATENT OFFICE.

JOSEPH HABERKORN, OF CHICAGO, ILLINOIS.

PAPER CUTTER.

Application filed August 5, 1925. Serial No. 48,206.

This invention relates particularly to a cutter of this kind for use with rolls of paper, and is used particularly by newspaper printers or pressmen, although of course it may have a more general use wherever applicable.

Among the objects of the invention are: to provide a cutter of this kind which can be adjusted for severing one or more thicknesses of paper; to prevent the cutter from gouging any more than the predetermined thicknesses; to prevent the severed edges of the cut paper from being folded upon themselves in cutting the paper; to eliminate any electrifying effect by the use of a fiber cutter; and in general to produce the construction herein shown and described.

In the accompanying drawings illustrating this invention, Figure 1 is a side elevation of a paper cutter constructed in accordance with the principles of this invention; Figure 2 is a section of the paper cutter showing its action with a single sheet of paper; Figure 3 is a bottom view; Figure 4 is a view of the rear end; Figure 5 is a section taken on the line 5—5 of Figure 2; and Figure 6 is a perspective of the cutter member.

In printing from rolls of paper it has been the practice to cut or score the roll, wherever necessary, with a sharp instrument, which not only severs one sheet, but also may damage a number of layers beneath the outermost sheet, thereby resulting in much wastage of paper and also a great wastage of time in removing the paper which is scored or damaged on the roll. It is found that if a sheet is even partially severed or is cut a part of the way across, it is very difficult to feed it in a printing press as the paper is liable to tear and become wrapped upon the ink rollers from which it is hard to remove. The only satisfactory way is to completely sever a sheet or a number of thicknesses of the roll of paper from one edge to the other, at the same time insuring that the severed sheet or thicknesses, and only those, are damaged by the cutter. In using a steel cutter, it is found that the cutter element has a certain attraction or electrifying effect upon the paper which makes the paper stick to it, and the point of the instrument tends to gouge deeper as it passes through the paper from one side of the roll to the other, thereby damaging

more thicknesses on one side than it does on the other.

The present invention is designed and intended to overcome these objections by providing a cutter member which is substantially flat on the bottom with a point upon which the paper rides so that only the thicknesses engaged thereby will be severed, a space being provided at the rear of the cutting portion for receiving the edges of the paper so that they will not be doubled over even though they are not cut smoothly as with a knife.

Referring more particularly to the drawings, a hold or casing member 1 is formed with a rounded end 2 and sides 3 to cover a recessed portion 4, and the lower front edge is inclined or rounded upwardly at 5 as shown more clearly in Figures 1 and 2. The rear edges of the side wings 3 are rounded downwardly at 6; the upper or back portion of the holder is formed with a countersunk slot 7, and the rear edge of the cutter is formed with a projection or tooth 8.

A cutter member 9, as shown more clearly in Figure 6, is preferably made of fiber, hard rubber or some other suitable material, the main portion of which is substantially the same width as the holder member 1, so that it is flush with the outer face of the holder member. At the rear upper edge are a number of teeth 10 adapted to engage the corresponding teeth 8 of the holder member 1 and in the upper edge is a threaded opening 11 to receive a screw 12 inserted through the slot 7 for holding the member 9 in place and in engagement with any one of the teeth 10. The lower front edge of the cutter member is reduced in thickness to form an extending tongue 13, the front edge of which is rounded downwardly at 14 with a further reduction 15 at the tip thereof so that when viewed from the bottom as shown in Figure 3 the cutting tip 16 is simply a flat appearing tongue of considerable width, rounded at the outer end. A cutting surface 17 is really formed by the tip reduction 15 above the front surface of the tip 16 so that the paper is broken irregularly rather than cut as by a sharp knife or other instrument.

The extending tongue 13 is formed by reducing the sides of the cutting member 9 along the arcs or curves 18 which makes the member freely adjustable in the holder 1 and the lower edge of the member 9 is formed

with a recess 19 extending upwardly from the lower face of the tongue about midway of the length of the cutter member 9, the recess 19 being slightly greater in width than the width of the tongue member 13. The object of this construction is to provide a space for the severed edges 20 of a sheet 21 which is cut thereby, as it has been found that if this portion of the cutter member is left flat the edges will be folded over upon themselves instead of remaining smooth as indicated in Figure 4. This is of great importance in feeding the edge of a sheet into a printing press, for if the sheet is folded along part of the edge and unfolded along another part, it may be picked up by the printing rollers and torn, or otherwise folded or crumpled in an undesirable way.

20. In operating this cutter, the front tip 16 is adjusted to engage one or more thicknesses of paper or other material which is to be severed; the tip is engaged with the sheet or sheets at the edge of the roll and 25 by running the instrument flatly over the roll from one edge to the other, the predetermined number of sheets or thicknesses are completely severed from one edge to the other. Even if the cutter is stopped and 30 withdrawn before a complete cut is made, a reinsertion of the cutter through the cut portion will engage only the same number of sheets, and no more, and the transverse cut will be completed. It is practically impossible to start the cutter at any place except the edge of the roll or sheet, because 35 the tongue is so flat and close to the holder that it will not engage the sheet at the edge thereof. Thus the cutter will not gouge into 40 a sheet; it will not take more than its predetermined thicknesses, which is determined by the setting of the cutting member, and even if held in the hand or carried in one's 45 pocket there is no danger of it cutting except in the authorized or regular manner of its use as above explained.

I claim:

1. In a paper cutter, a holder member having a recess at one side thereof, a cutter member adjustable in the recess and having a tongue extending to the outer edge of the recess and a recess at the rear end of the tongue, and means comprising a projection on one part and teeth on another adjustable relatively to vary the position of the cutter member in the holder.

2. In a paper cutter, a holder having a recess in one edge, a cutter member fitting within the recess and having a tongue flat on one side of less width than the width of the recess and with sides spaced apart more than the width of the tongue at the rear of the tongue to allow sheets severed by the cutter member to slip by without creasing or 65 folding them.

3. In a cutter of the class described, a holder member having a recess opening from one edge thereof and the extremity of this edge rounded upwardly from the recess, of a cutter member insertable within the recess and having a flat tongue with a cutting edge at the tip, the holder and the cutting member being inclined correspondingly so that a longitudinal movement of the cutter member in the holder will advance or withdraw the tongue at the recessed edge of the holder and means for adjustably fastening the cutter member within the holder.

4. In a cutter of the class described, a holder having a recess opening from one edge thereof, a cutter member insertable in the recess and having a flat surface to project at the edge of the recess, the inner surface of the recess being inclined and formed with a projection at one end thereof, the cutter member being correspondingly inclined and provided with a plurality of teeth for engaging the projection, and means for fastening the cutter member adjustably in the holder.

5. In a cutter of the class described, a holder having a recess opening from one edge thereof, the inner surface of the recess being inclined and having a projection at the end, a cutter member having a flat tongue and an opposite edge inclined thereto and having teeth to engage the projection of the holder, and means to fasten the member in the holder and to adjustably engage any one of the teeth with the said projection.

6. In a cutter of the class described, a holder having a recess in one edge, a cutter adjustable therein having a tongue flat on one side with a cutting surface extending rearwardly from the tip thereof, and a recess at the rear of the tongue having spaced flat edges in the same plane with the flat side of the tongue.

7. In a cutter of the class described, a holder having a recess therein formed by side wings, a cutter member having a portion the width of the holder to be inserted in the recess and having a reduced flat side forming a tongue to project at the edge thereof, the thicker portion of the cutter member being recessed at the rear of the tongue to form two parallel side extensions, the faces of which are in the same plane with the flat side of the tongue.

8. In a cutter of the class described, a holder having a recess in one edge, the extremity of this edge being rounded away, and an extension with an inclined surface at the end of which is a toothed projection, of a cutter member therefor of substantially the same thickness as the holder having an inclined surface adapting it to fit against the inclined surface of the extension and having teeth to engage the tooth of the extension, the cutter member also

having a tongue reduced in width, flat on the outer side with a rounded extremity and with a cutting portion extending rearwardly from the opposite face of the tip, the tongue being less in width than the recess and affording a space at both sides between it and the edges of the recess of the holder, the cutter member being recessed at the rear

end of the tongue leaving side projections, and fastening means insertable through the projection of the holder into the cutter member adjustable for the variable engagement of the teeth of the holder and cutter members.

JOSEPH HABERKORN.
